this Attorney,

UNITED STATES PATENT OFFICE.

GEORGE H. STRONG AND JOHN I. CARR, OF CHICAGO, ILLINOIS, ASSIGNORS
TO LAWRENCE W. TATUM, OF CLEVELAND, OHIO.

TOOL-HOLDER FOR GRINDSTONES.

SPECIFICATION forming part of Letters Patent No. 277,958, dated May 22, 1883.

Application filed March 19, 1883. (No model.)

To all whom it may concern:

Be it known that we, GEORGE H. STRONG and JOHN I. CARR, citizens of the United States of America, residing at Chicago, in the county of Cook and State of Illinois, have invented certain new and useful Improvements in Tool-Holders for Grindstones, of which the following, in connection with the accompanying drawings, is a specification.

10 In the drawings, Figure 1 is a side view of a tool-holder embodying our invention. Fig. 2 is a top or plan view of the same. Fig. 3 is a like representation in detail, showing a modification in the form of the jaw. Fig. 4 is a side view of the parts shown in Fig. 3. Fig. 5 is a detail of the base or lower parts of the holder, and Fig. 6 is a detail showing a joint at the forward end of the supporting-arm.

15 Like letters of reference indicate like parts.

20 A represents the grindstone, and B its frame. C is the base-piece of the tool-holder. This base-piece has a horizontal part, a, adapted for attachment to the frame A, and a vertical part, a', in the top of which is a deep groove, a''.

25 D is a standard or supporting-arm. The arm D has a horizontal part, b, and a vertical part, b', and the horizontal part has in it a groove, b''.

E is a set-screw entering the part a', and 30 having its inner end in the groove b''. By this means the arm D is rendered adjustable or capable of being moved back and forth or to and from the stone A. It is also prevented from being tilted, and is retained firmly in its 35 place by means of the screw E.

F is a cylindrical bar passing horizontally through the upper end of the arm D.

G is a screw entering the upper end of the arm D. The inner end of this screw enters the 40 bar F and performs the function of retaining it rigidly in its place.

H is a plate having depending ears or flanges c c, through which the bar F passes freely, the said plate being fitted to the said bar, so as to be capable of being tilted thereon, and also so as to be capable of sliding laterally.

H' is a vertical projection on the plate H, and I is a screw passing through the said projection.

J is a plate pivoted to the plate H, and J' is a bridge-bar forming a part of the plate J.

K is a screw passing through the bar J'.

L is a handle attached to the plate J. This handle, however, may be attached to the plate 55 H instead of to the plate J.

M is the knife or cutter of a carpenter's plane.

To use the parts now described for the purposes for which they are intended we arrange the tool to be sharpened underneath the bar J', 60 and secure it there rigidly by turning the screw K down firmly upon it. We also set the plate J so that the tool will be held at any angle desired with relation to the stone A, and bind the said plate temporarily in that position by 65 means of the screw I. The plate H and the parts above it we also tilt, if need be, in such a position as to bring the edge of the tool in proper relation to the grindstone, so that the edge shall have the proper bevel, when the 70 edge of the tool may be retained in contact with the stone, so as to bear more or less thereon, by raising the handle L. The tool may be moved to and from the stone by loosening the screw E and sliding the arm D in the base C. 75 Then by tightening the said screw the said arm will be retained in the position in which it is set. To move the tool laterally, slide the plate H on the bar F.

To adapt the tool-holder to hold such tools 80 or devices as harvester-sickles, knives, and like tools, we employ, in lieu of the plate J, the pivoted jaw N, and in that case we locate the part H' and the screw I, as shown by the full lines in Fig. 3, instead of at far side of the 85 plate H; also, where the jaw N is employed, it may be expedient to connect the bar F to the standard D by means of a knuckle-joint, as shown in Fig. 6, so that the knife or blade may be properly clamped and presented to the 90 stone A.

The screw G performs the function of preventing the bar F from moving laterally when the plate H is moved laterally thereon; but this movement of the bar F may be prevented 95 in any suitable or well-known way—as, for example, by fitting the said bar tightly into the arm D. However, should the said bar become loose, the screw G will be found serviceable for the purposes set forth.

Having thus described our invention, what we claim as new, and desire to secure by Letters Patent, is—

1. The combination, in a tool-holder for 5 grindstones, of the grooved base C, the screw E, the sliding standard D, the bar F, the tilting plate H, the screw G, a rotary or pivoted jaw for receiving the tool to be sharpened, the screw I, and a screw for binding the tool in 10 the jaw, substantially as and for the purposes specified.

2. The combination, in a tool-holder for

grindstones, of the sliding standard D, the cylindrical bar F, the tilting and sliding plate H, a rotary or pivoted jaw for receiving the tool 15 and mounted on the said plate, and the binding-screws K, I, and G, substantially as and for the purposes specified.

GEORGE H. STRONG.
JOHN I. CARR.
